UNITED STATES PATENT OFFICE.

HORACE CLARENCE MARSH, OF ROCKFORD, ILLINOIS.

DESIGN FOR A MITER-BOX.

SPECIFICATION forming part of Design No. 19,629, dated January 28, 1890.

Application filed October 26, 1889. Serial No. 328,326. Term of patent 14 years.

To all whom it may concern:

Be it known that I, HORACE CLARENCE MARSH, a citizen of the United States, residing at Rockford, in the county of Winnebago and State of Illinois, have invented and produced a new and original Design for a Miter-Box and Picture-Frame Clamp, of which the following is a specification, reference being had to the accompanying drawings, forming 10 a part thereof.

Figure 1 shows a plan view, and Fig. 2 an edge view.

My design relates to a trifurcated miter-box and picture-frame clamp, which consists, 15 essentially, of three branches or trifurcations

A, B, and C, said parts being arranged as shown in the drawings.

The novel feature of the design consists of the branches or trifurcations A, B, and C, when designed and arranged as shown in the 20 drawings.

What I claim is—

The design for the miter-box and picture-frame clamp, comprising the branches or trifurcations A, B, and C, designed and arranged as shown and described. 25

HORACE CLARENCE MARSH.
